UNITED STATES PATENT OFFICE.

PETER FELDEN, OF CHICAGO, ILLINOIS.

ROCKING-CHAIR.

SPECIFICATION forming part of Letters Patent No. 242,442, dated June 7, 1881.

Application filed August 30, 1880. (No model.)

To all whom it may concern:

Be it known that I, PETER FELDEN, of Chicago, in the county of Cook and State of Illinois, have invented a certain new and useful 5 Improvement in Rocking-Chairs, of which the following is a specification.

The object I have in view is to produce strong, durable, noiseless, and simple spring-connections for platform rocking-chairs which 10 will not interfere with the bottom of the seat nor with the cross-rails of the platform, and will hold the chair firmly upon the platform and confine its rocking movement within safe limits, and will prevent both lateral and longitudinal slipping of the rockers on the base-rails without the use of stops or guides, and 15 will at the same time give an exceedingly easy movement to the chair-body.

My invention consists in the peculiar construction of the springs and the means for attaching them to the rockers and side rails of the platform, as fully hereinafter explained, and pointed out by the claims.

In the accompanying drawings, forming a 25 part hereof, Figure 1 is an elevation of the inside of one of the rockers of the body and one of the side rails of the platform or base with my improved spring-connection attached thereto. Fig. 2 is a top view of the spring, and Fig. 30 3 a cross-section through one of the bracket-irons and one side of the spring on line 3 3.

Like letters denote corresponding parts in all three figures.

A is one of the side rails of the platform or 35 base, and B the corresponding rocker of the body of a platform rocking-chair, such rocker resting directly upon said side rail.

C is a continuous plate-metal spring, the upper and lower sides of which, at the center, are 40 secured, preferably, by rivets to the horizontal wings *a* of cast-metal bracket-iron D D'. The vertical wings *b* of these bracket-irons have countersunk holes, through which wood-screws are turned for securing the bracket-irons to 45 the rocker and base-rail. On each side of the bracket-irons the two parts of the continuous plate-spring are bent toward each other, as shown at *c*, and are then spread apart, and form rounded loops *d*. These loops *d* project 50 considerably more below the upper surface of

the base-rail than above it, so as not to interfere with the seat-bottom in rocking.

The continuous spring is formed of a straight piece of plate metal, which is bent into the shape shown and the ends lapped, such lapped 55 ends being riveted to one of the bracket-irons.

The horizontal wings *a* of the bracket-irons have shoulders *e*, against which the spring abuts, such shoulders assisting the rivets to resist the lateral strain, and keeping the spring 60 from scraping against the rocker or base-rail.

The continuous spring extends parallel to the rocker and base-rail, and when secured to the inner side thereof is spread apart somewhat, so as to draw them firmly together. The 65 spring, while allowing a free and easy rocking movement within safe limits, has great lateral stiffness, preventing any lateral displacement of the chair-body on the platform. The spring also, by being continuous, and by reason of 70 extending on both sides of the bracket-irons, prevents the rocker from slipping longitudinally on the side rail of the platform, since one part of the spring counteracts the tendency of the other part to effect such a slipping movement in rocking. If the spring were made a 75 half-spring—that is, were extended only on one side of the bracket-irons—it would cause the rocker to slip longitudinally on the base-rail in rocking, and would therefore make a noise. 80 The continuous spring can also be made of lighter steel-plate and cheaper than the half-spring, and, by extending on both sides of the bracket-irons, it need not project so close to the front cross-rail of the platform. 85

It will be understood that two of my spring-connections are used on each chair, one being secured to the inner side of each rocker of the body and the corresponding side rail of the 90 platform or base.

I wish it understood that I do not claim as any part of my invention the half-spring for this purpose, some of the disadvantages of which have just been set forth.

What I claim as my invention is—

1. In a platform rocking-chair, the combination, with the base-rail A and the rocker B, resting directly upon the base-rail, of the bracket-irons D D', secured rigidly to said rocker and base-rail at or near their center, and the 100

continuous double plate spring C, bent from a single piece of metal and secured rigidly at its center to said bracket-irons, such spring extending on both sides of the bracket-irons parallel with the rocker and base-rail, and having free ends, substantially as described and shown, for the purpose set forth.

2. In a platform rocking-chair, the combination, with the base-rail A and rocker B, of the bracket-irons D D' and the continuous plate-spring C, secured to such bracket-irons and

extending on both sides thereof parallel to the base-rail and rocker, said spring being bent inwardly at c and outwardly to form rounded loops d at its ends, which loops extend more 15 below than above the top of the base-rail, substantially as described and shown.

PETER FELDEN.
